UNITED STATES PATENT OFFICE.

FRANCIS A. CLOUDMAN, OF CUMBERLAND MILLS, MAINE, ASSIGNOR TO S. D. WARREN & CO., OF BOSTON, MASSACHUSETTS.

CLEARER FOR PULP-SCREENS.

SPECIFICATION forming part of Letters Patent No. 356,926, dated February 1, 1887.

Application filed October 19, 1886. Serial No. 216,647. (No model.)

To all whom it may concern:

Be it known that I, FRANCIS A. CLOUDMAN, of Cumberland Mills, county of Cumberland, and State of Maine, have invented an Improvement in Clearers for Pulp-Screens, of which the following description, in connection with the accompanying drawings, is a specification, like letters on the drawings representing like parts.

10 This invention in paper-pulp screens has for its object to effectually keep open or clear the slits in the screen-plate. To do this I have provided a rocking plate or cleaner which is located below the screen-plate, and is adapted 15 to draw the finer pulp through the said screen on the downward movement of one half of the said plate, and to open or free the interstices of the said screen on the upward movement of the other half of the said plate, one half of 20 the said plate being thus subjected to suction, while the other half is subjected to pressure.

25 My invention therefore consists, essentially, in a pulp-treating machine, of a pulp-vat and a fixed or stationary screen-plate therein, combined with a rocking plate located below the screen-plate, and means, substantially as will be described, to impart a rocking motion to the said rocking plate, as and for the purpose hereinafter specified.

30 Other features of my invention will be pointed out in the claims at the end of the specification.

Figure 1 is an isometric view of a pulp-screening apparatus provided with my improved rocking plate or cleaner; Fig. 2, a side elevation of Fig. 1; Fig. 3, a transverse section through the pulp-vat, showing a modified form of rocking plate or cleaner; and Fig. 4, a detail showing a part of the screen-plate.

40 The pulp vat or box A, supported upon legs A', or in other suitable manner, contains within it a screen-plate, a, of usual construction, secured to a frame, a', fastened to the vat or box A, the said screen-plate being supported near 45 its center by a longitudinal rail, a³. (See dotted lines, Fig. 2.) Below the screen-plate a, and in close proximity to the rail a³, is a shaft, a⁴, having its bearings in glands a⁵, supported in the sides of the vat or box A, only one gland 50 being shown in Fig. 1.

The shaft a⁴, herein shown as rectangular for the greater part of its length, has, for the best results, secured to its upper and lower sides plates b, which incline from the said rail toward their ends, where they are united in 55 any suitable manner.

The lower plate, b, for the best results, has secured to or forming part of it a semicircular plate, b'.

60 The shaft a⁴ and the plate b, attached thereto, have a rocking motion imparted to them by a sweep, b³, slotted at its lower end to receive a crank-pin, c, fastened to a yoke, c', pivotally connected at c² (see Fig. 2) to a fly-wheel, c³, the other end of the yoke c' being adjustably 65 secured by a bolt, c⁴, inserted in holes c⁵ in the said fly-wheel, the adjustment of the bolt c⁴ enabling the stroke of the sweep, and thereby of the rocking plate, to be regulated as desired, rotation being imparted to the fly-wheel 70 by a main shaft, d, to which it is secured. As the plate b is rocked through the mechanism described, one half, as 2, of said plate exerts a suction upon the pulp in the vat above the screen-plate, while the other half, as 3, forces 75 some of the fine stuff lying upon it back again and through the interstices of the screen-plate.

75 The force with which the pulp is drawn through the screen-plate may be varied, according as a coarser or finer stock is desired, 80 by means of dash-boards e at opposite sides of the screen-plate, as shown in Fig. 2. Each dash-board e is adjustably fastened to the vat or box A by screws e', extended through openings 12 in the dash-board, only one such opening being shown in Fig. 1, the said screws being adjustable in slots e².

85 Pulp contained in the vat A will be drawn through the screen while one half, as 2, of the rocking plate is being moved downward, the 90 suction being continued until the end of the said plate clears the dash-board e, when all suction of pulp through the screen by the said descending half of the rocking plate is stopped. As the said half of the rocking plate is moved 95 upward toward the screen-plate it forces some of the fine pulp remaining upon its surface and lodged, it may be, on the screen up through the interstices of the screen-plate, thus freeing them and agitating the pulp above 100

the screen-plate, the other half of the rocking plate being on its downward movement and drawing the pulp through the screen-plate at its side of the vat. The fine pulp passes from 5 the vat A, through the opening 20 in its side, to the paper-making machine.

The semicircular part b' effects the least possible agitation of pulp below the screen-plate; but the said plate is not absolutely essential, 10 as it may be omitted and the rocking plate, as shown in Fig. 3, be used with advantageous results.

I do not desire to limit my invention to the particular mechanism shown for imparting a 15 rocking motion to the shaft a' and its attached plate.

I do not claim a rising and falling screen-plate.

I claim—

- 20 1. In a pulp-treating machine, a pulp-vat and a fixed or stationary screen-plate therein, combined with a rocking plate located below the screen-plate, and means, substantially as described, to impart a rocking motion to the 25 said rocking plate, for the purpose specified.
2. In a pulp-machine, a pulp-vat, a screen-plate therein, and dash-boards secured to the vat at opposite sides of the said screen-plate,

combined with a rocking plate located below the screen-plate, and means, substantially as 30 described, to impart a rocking motion to the said rocking plate, for the purpose specified.

3. In a pulp-machine, a pulp-vat, a screen-plate therein, and adjustable dash-boards secured to the vat at opposite sides of the said 35 screen-plate, combined with a rocking plate located below the screen-plate, and means, substantially as described, to impart a rocking motion to the said rocking plate, for the purpose specified.

4. In a pulp-machine, a pulp-vat and screen-plate therein, combined with a rocking plate composed of an inclined upper plate and a semicircular lower plate, and located below the screen-plate, and with means, substantially 45 as described, to impart a rocking motion to the said rocking plate, substantially as and for the purpose set forth.

In testimony whereof I have signed my name to this specification in the presence of two sub- 50 scribing witnesses.

FRANCIS A. CLOUDMAN.
